(57) **CLAIM**

We claim, the ornamental design for a plug connector, as shown and described.

DESCRIPTION

FIG. 1 is a front perspective view of a plug connector showing our new design;

FIG. 2 is a front view thereof;

FIG. 3 is a rear view thereof;

FIG. 4 is a side view thereof;

FIG. 5 is another side view thereof;

FIG. 6 is a top plan view thereof;

FIG. 7 is a bottom plan view thereof; and,

FIG. 8 is a rear perspective view thereof.

In the drawings, the broken lines depict unclaimed environment only and form no part of the claimed design.
